UNITED STATES PATENT OFFICE.

LEIGHTON L. BROWN, OF MINNEAPOLIS, AND CHARLES H. PATEK, OF BRAINERD,
MINNESOTA.

DAMPER.

1,079,833.

Specification of Letters Patent.

Patented Nov. 25, 1913.

Application filed November 7, 1912. Serial No. 729,976.

To all whom it may concern:

Be it known that we, LEIGHTON L. BROWN, of Minneapolis, Hennepin county, Minnesota, and CHARLES H. PATEK, of Brainerd, 5 Crow Wing county, Minnesota, have invented certain new and useful Improvements in Dampers, of which the following is a specification.

Our invention relates to dampers for 10 smoke flues and the object of the invention is to provide a damper which will effectively check the draft through the flue or may be swung down against the wall of the flue to provide practically an unobstructed passage 15 therethrough.

A further object is to provide a damper which can be easily and quickly mounted in a pipe in place of an ordinary damper without cutting or defacing the walls of the pipe. 20 Other objects of the invention will appear from the following detailed description.

The invention consists generally in various constructions and combinations, all as 25 hereinafter described and particularly pointed out in the claims.

In the accompanying drawings forming part of this specification, Figure 1 is a sectional view through a smoke pipe, showing 30 our invention applied thereto, Fig. 2 is a plan view of the spindle, Fig. 3 is a detail view of the spindle on which the damper is mounted.

In the drawing, 2 represents a section of 35 smoke pipe, cylindrical in form, as usual in pipes of this kind.

3 is a pin that is adapted to be inserted through holes in the wall of the pipe, one end of the pin having a head 4 which is seated 40 against the pipe wall. The opposite pointed end passes through the wall of the pipe on the other side of the center and is secured by suitable means, such as a cotter pin 5. The pin 3 has a longitudinal 45 recess 6 therein adapted to receive a flattened spindle 7 which is pivoted at 8 on the pin 3 near the head 4 and has an exteriorly threaded arm 9 which projects outwardly and downwardly at an angle to the spindle 50 7 and is provided with a movable counter-balance weight 10. The recess in the pin 3 is of sufficient depth to bring the outer face of the spindle flush, substantially, with the surface of the pin so that it will not obstruct

the pushing of the pin through the hole in 55 the pipe.

Upon the spindle 7 is a damper blade 11 which is preferably curved in cross section to fit the concave inner surface of the pipe when the blade is swung to a substantially 60 vertical position, thereby allowing the free passage of the air currents through the flue. We prefer to provide a socket 12 in the blade 11 into which the spindle 7, preferably tapered, is thrust, and we also prefer to 65 provide ribs or corrugations 13 in the blade which will serve to strengthen it and permit the use of thinner material and will also increase the resisting surface for the draft to act upon. The spindle is preferably provided with a notch 14 therein to receive the 70 loop formed in the damper blade, the edges of the loop contacting with the end walls of the recess and locking the blade on the spindle. We are thus able to assemble the 75 parts easily and quickly, as no bolting or riveting of the blade to its supporting spindle is required.

Evidently the damper blade can be balanced at any desired angle in the pipe by 80 the adjustment of the counter-weight. The pin 3 may be thrust into the damper holes in the pipe from which an ordinary damper has been removed, and we are thus able to install our device without making any 85 change in the pipe or cutting new or larger holes therein. Our device is adapted, therefore, for use with flues already installed as well as those that are being set up.

We claim as our invention:—

1. The combination, with a pipe, of a spindle pivotally supported thereon and projecting into the pipe, said spindle having an arm projecting outwardly at an angle thereto, and a weight adjustably mounted on 95 said arm, said spindle being adapted to swing to a position against the inner surface of the pipe, said arm having an unobstructed travel to permit said spindle to assume a position in line with said pipe and against the 100 wall thereof, and a damper blade mounted on said spindle and curved in cross section and fitting snugly against the curved wall of the pipe when said spindle is swung to a position against said wall.

2. The combination, with a pipe, of a pin fitting into holes therein and extending across the pipe from side to side, a spindle

pivoted on said pin at one end thereof and provided with an arm extending outwardly at an angle to said spindle, a damper plate mounted on said spindle, and a weight adjustably mounted on said arm.

3. The combination, with a pipe having holes therein, of a pin fitting into said holes and having a head at one end seated against the surface of the pipe, a spindle pivoted on said pin near one end thereof, and a damper plate having a socket therein to receive said spindle.

4. The combination, with a pipe, of a pin extending across the pipe and having its ends supported in the walls of the pipe and provided with a longitudinal recess, a spindle pivoted at one end on said pin and adapted to fit into said recess, and a damper plate having a socket to receive said spindle.

5. The combination, with a pipe, of a head having a part fitting within a hole in the wall of the pipe, a spindle pivoted on said head and provided with a tapered inner portion to extend across the interior of the pipe, a damper blade having a socket to receive said tapered inner portion, said spindle having an outwardly projecting threaded portion and an interiorly threaded weight

to engage the threads of said threaded portion.

6. The combination, with a pipe, of a spindle pivotally supported thereon and projecting into said pipe, a damper blade having a socket to receive said spindle and held thereon by frictional engagement between said plate and said spindle, said spindle having an arm extending outwardly at an angle therefrom and a weight adjustably mounted on said arm.

7. The combination, with a pipe, of a spindle pivotally supported thereon and projecting into the pipe and provided with a notch or recess, a damper blade having a socket into which said spindle is inserted, said blade having a part to snap into said notch and prevent the accidental separation of said blade and spindle, and a weighted arm carried by said spindle.

In witness whereof, we have hereunto set our hands this fourth day of November, 1912.

LEIGHTON L. BROWN.
CHARLES H. PATEK.
